FURNACE STOKER

Emory O. White, Albertville, Ala.

Application July 11, 1945, Serial No. 604,391

2 Claims. (Cl. 110—45)

1

This present invention relates to improvements in stoker fired furnaces and involves a construction fitting the stoker to the furnace and vice versa.

Automatic coal burning stokers were originally developed for the purpose of installing them in the conventional furnace by removing the grates and mounting the retort through the ash pit door.

Earlier installations necessarily made from the front left the stoker very much in the way and made the removal of the clinkers inconvenient. To overcome these disadvantages many of the present furnaces equipped for stoker firing have a side entrance for the stoker. Aside from this the conventional ash pit construction has been followed and a practical arrangement for making the installation from either side is lacking. The importance of such an arrangement appears from the fact that the condition of the basement often makes it necessary to make the installation from one particular side.

Furthermore the usual method of installation is inconvenient and costly and tends to shorten the life of the retort. Many installations are made by filling in sand around the retort and laying a refractory hearth on top of the sand. The sand collects moisture during the summer season which results in the rusting out of the retort and wind box. A further shortcoming is found in the inefficient construction of the hearth and its support. Both often give way and expose the lower part of the retort and wind box to excessive heat causing them to burn out. In an effort to overcome this a ventilated installation has been developed which, however, still clings to the antiquated ash pit construction. The only change in this last installation is the substitution of a plate for the sand as a support for the refractory hearth, the ash pit itself being open to the air instead of being filled with sand.

The present invention starts with the conception that the furnace and stoker represent a unit in which one must be fitted to the other. In order to fit the furnace to the stoker, it is necessary to support the furnace above the ground by legs, thereby eliminating the ash pit entirely. The closed bottom of the furnace has only an opening for the retort, the opening being reinforced by a stiffening ring. The shape of the transverse cross section of the retort is immaterial. The stiffening ring fits into a groove lined with asbestos rope or furnace cement and both make an air tight seal for the bolted joint

2

between retort and furnace. The fastenings are so located that the windbox is reversible and can be turned to right and left (Figure 1).

The outer end of the windbox is connected to the casing in a manner giving it a finished appearance.

The construction hereinbefore outlined has several advantages one of which is a quick and easy cost saving installation; another advantage arises from the device of the installer between the two sides of the furnace through which the windbox extends. A third advantage lies in the longer life of the windbox and retort. A fourth advantage is the finished appearance of the casing and outer end of the windbox connected thereto.

Other objects and advantages of my improved furnace will be obvious to persons skilled in this art after the construction and operation is understood from the following detailed description read in connection with the accompanying drawings in which:

Figure 1 is a vertical section of the preferred embodiment of my invention;

25 Figure 2 is an enlarged vertical section on line 2—2 of Figure 1;

Figure 3 is a horizontal section;

Figure 4 is a front end view and section on line 4—4 of Figure 3;

30 Figure 5 is a vertical transverse section through the windbox.

In the drawings in which like characters of reference designate corresponding parts throughout the several views, numeral 2 denotes the conventional casing within which the furnace 3 is supported on legs 4. The lower portion of the furnace forms a combustion chamber the cylindrical wall of which is lined with fire brick 5. The bottom 6 of the furnace is slightly dished and has a central aperture surrounded by a cylindrical flange 7 which extends above and below the bottom.

A windbox 8 has a transverse oblong vertical section (Figures 2, 5) and an inner semicylindrical end portion concentric with the furnace (Figure 3). Angle irons 9 are attached by welding or otherwise to opposite ends of the flat vertical sides of the windbox and have in their horizontal arms bolt openings 10 for the lower portions of bolts 11 and nuts 12 of which bear against the lower surfaces of the arms. The upper ends of the bolts are secured to and in lugs 13 attached or formed upon the lower surface of the furnace bottom. The top of the windbox has in its semi-cylindrical end a cir-

cular opening 14 formed within an inwardly extending flange 15. A cylindrical flange 16 extends upwardly at right angles to the first flange and is partly a continuation of the semi-cylindrical wall forming the inner end of the windbox. The flange 16 encloses the downwardly extending portion of the cylindrical bottom flange 7.

The retort 17 consists of an outer cylindrical portion 18 the lower edge of which is secured by welding or otherwise to the inner marginal portion of the flat inwardly extending flange 15 and defines with the flange 16 an annular space. The bottom of this space is filled with asbestos rope or furnace cement 19 and the annular space also receives the lower portion of the bottom flange 7 extending below the underside of the bottom. This construction seals the gases from the space between the furnace and casing.

The annular top surface of the bottom is covered with fire bricks 20 the inner ends of which form with the adjacent outer surface of the outer retort portion an annular space filled with furnace cement 21 or a similar substance. The outer portion of the retort extends above the horizontal top surface of the fire bricks lining the bottom of the furnace and is provided in its upper margin with a plurality of a radial openings 22 which admit air from the windbox to the combustion chamber. The top of the outer retort portion is formed by a flat annular portion 23 from the inner retort portion 24, representing the frustum of an inverted cone and provided at the upper end with a series of radial air openings 25.

The lower narrow end of the inner retort section is surrounded by an upwardly extending flange 26 on the horizontal mouth of a feed tube 27 which curves laterally and downwardly and extends horizontally towards and through the side wall of the furnace casing.

The windbox has an outer vertical end wall 28 which is arranged to lie outside of the outer side of the casing wall and has an aperture with an inwardly extending cylindrical flange 29 for the outwardly extending portion of the feed tube. The windbox is provided on all sides with an outwardly extending flange 30 positioned inwardly of the end wall of the windbox and secured by bolts 31 to the casing.

The feed tube 27 extends outwardly of the windbox (Figures 1, 3) and is provided in the end portion adjacent the outer side of the end wall of the windbox with a pair of radial threaded apertures which receive each a bolt 32. The bolts 32 bear with their inner ends against the outer side of an extension tube 33 which extends into the feed tube.

The end wall of the windbox has on either side of the feed tube an aperture 34, one for an air tube 35 and the other for a clean out tube 36.

The above description and accompanying drawing (Figure 1) clearly indicate that the assembly comprising the retort, windbox, feed tube

can be connected to a furnace through either side wall of the casing. The combustion chamber has a double seal of heat resisting material against the escape of gases.

I have specifically described the preferred embodiment of my invention in all details in order to impart a full, clear and exact understanding of my invention. I do not desire, however, to be understood as confining myself to the precise construction and relative arrangement of parts as disclosed, my invention being defined by my appended claims within the scope of which changes in structure and in arrangement may be made without departure from my invention.

15. What I claim and desire to secure by Letters Patent is:

1. A stoker-fed warm air heating plant comprising a furnace having a bottom supported above the floor and provided with a flanged opening in the bottom thereof, a retort in the opening having inner and outer parts joined at their upper ends in spaced relationship and each having a series of tuyère apertures, a wind box having an opening concentric with said first opening and a flange surrounding both openings and the flange of the first mentioned opening, heat resisting sealing means between the flanges and the wind box, a connection between the wind box and furnace bottom, fuel feeding means connected to the inner part of the retort and extending through the wind box, an air tube extending into the wind box, and a cleaner tube accessible from the outer side of the furnace.

2. A warm air heating plant comprising a leg supported furnace having a centrally apertured bottom and a brick lined combustion chamber disposed thereabove, a cylindrical flange in the aperture, a retort in the flange and including radially spaced outer and inner parts joined at their upper ends, said retort parts being apertured above the combustion chamber bottom, a wind box having an opening with a cylindrical flange surrounding the first flange and with a radial flange underlying said first flange, and heat resisting sealing means between said flanges.
